DESIGN FOR A COMBINATION FOOD CHOPPER AND GRINDER

Clarence P. Hornung, Hempstead Lake Park, N. Y.

Application February 15, 1944, Serial No. 112,593

Term of patent 7 years

(Cl. D55—1)

To all whom it may concern:

Be it known that I, Clarence P. Hornung, a citizen of the United States, residing at Hempstead Lake Park, county of Nassau and State of New York, have invented a new, original, and ornamental Design for a Combination Food Chopper and Grinder, of which the following is a specification, reference being made to the accompanying drawing, forming a part thereof.

Fig. 1 is a perspective view of a combination

food chopper and grinder showing my new design.

Fig. 2 is a rear-elevational view thereof.

The other side of the article, not shown, is substantially like the side shown.

I claim:

The ornamental design for a combination food chopper and grinder, as shown and described.

CLARENCE P. HORNUNG.
